(57) CLAIM

I claim the ornamental design for a whisk, as shown.

DESCRIPTION

FIG. 1 is a top frontal left side perspective view of a whisk showing my design;

FIG. 2 is a bottom rear right side perspective view thereof;

FIG. 3 is a right side elevational view thereof; and,

FIG. 4 is a top plan view thereof.

The rod of the whisk is shown broken away in FIGS. 1-4 to indicate indeterminate length of the rod.
